UNITED STATES PATENT OFFICE.

OSCAR L. LAWSON AND JAMES H. REED, OF LYNN, MASSACHUSETTS.

SHUTTLE-DRIVE.

1,215,557.

Specification of Letters Patent. Patented Feb. 13, 1917.

Application filed March 23, 1915. Serial No. 16,453.

To all whom it may concern:

Be it known that we, OSCAR L. LAWSON, a subject of the King of Sweden, and JAMES H. REED, a citizen of the United States, residing at Lynn, county of Essex, State of Massachusetts, have invented a certain new and useful Improvement in Shuttle-Drives, of which the following is a specification, reference being had therein to the accompanying drawings.

Our invention has for its object a new and improved means for oscillating the shuttle of shoe sewing machines, particularly of the type shown in the prior application of Oscar L. Lawson, Ser. No. 841,752, filed May 29, 1914. The object of our present invention is to provide a shuttle drive which while giving the shuttle a rapid movement from the time the hook of the shuttle picks up the loop until the limit of movement in that direction is reached, and a slow movement in the other direction, shall be free from complicated cams having steep portions. In machines of this character, particularly those intended to be operated at very high speeds it has been found that vibration and rapid wear result where steep cam surfaces are employed. Our present invention therefore provides means for giving the shuttle the requisite movement by means of mechanism having easy movements. It is found that our improved shuttle drive can be run at high speeds with a minimum of vibration and wear.

The invention will be fully understood from the following description taken in connection with the accompanying drawings, and the novel features thereof are pointed out and clearly defined in the claim at the close of this specification.

In the drawings, Figure 1 is a side elevation of a machine embodying our invention.

Fig. 2 is a front elevation.

In the drawings, at 11 is shown a shuttle mounted on the shuttle shaft 12 and provided with a gear 13. At 14, is shown a gear sector mounted on an arm 16 pivoted at 15, the center of said pivot coinciding with the center of the pitch circle of the gear. The arm 16 is connected with a link 7 which is in its turn connected at 18 to a

lever 19 pivoted at 20 to the frame of the machine. The lever 19 is bent and is provided with a slot 21 resembling the arc of a circle about a center located nearer the arm 16, that is, above the slot 21. The curve of the slot is not an arc of a true circle, but is an irregular curve which experience has proved to be most satisfactory. At 22 is shown the main drive shaft provided with a crank disk 23 on which is a crank pin 24. The crank pin 24 is located in the arc shaped cam slot 21 formed in the lever 19. The crank pin rotates in the direction indicated by the arrow in Fig. 1 and during a part of its rotation gives the shuttle point a very slow movement because the curve of the cam slot partly neutralizes the movement produced by the rotation of the crank disk. During the remainder of the rotation of the crank disk, the movement is correspondingly accelerated by the curve of the cam slot. We are aware that shuttles have previously been driven by gear sectors but so far as we are aware the movement of the gear sector has been produced either by an oscillation of the shaft upon which it is mounted or by a crank producing a harmonic motion, but so far as we know no attempt has been made to give the shuttle the desirable differences in speed by any other means than by the use of cams.

What we claim is:

In a shoe sewing machine, the combination of a shuttle, a gear sector actuating said shuttle, a lever arm, operating the gear sector, a crank member having a crank pin, a lever having a curved slot in which said crank pin moves, said lever being pivoted on a line forming an extension of a chord of the curve of the cam slot and at a distance therefrom and a link connecting the lever arm of the gear sector and said slotted lever, said link being on the concave side of said curved slot.

In testimony whereof we affix our signatures, in presence of two witnesses.

OSCAR L. LAWSON.
JAMES H. REED.
